UNITED STATES PATENT OFFICE.

HENRY R. TOWNE, OF NEW YORK, N. Y., ASSIGNOR TO THE YALE & TOWNE MANUFACTURING COMPANY, OF STAMFORD, CONNECTICUT.

DESIGN FOR A RIM LATCH-CASE.

SPECIFICATION forming part of Design No. 29,895, dated December 27, 1898.

Application filed November 28, 1898. Serial No. 697,706. Term of patent 7 years.

To all whom it may concern:

Be it known that I, HENRY R. TOWNE, a citizen of the United States, and a resident of the city of New York, in the county of New York and State of New York, have invented and produced a new and original Design for a Rim Latch-Case, of which the following is a specification, reference being had to the accompanying drawings, forming a part thereof, in which—

Figure I is a front elevation of a rim latch-case and strike, showing my design. Fig. II is a side view of the same. Fig. III is an end view thereof.

As shown in the drawings, the leading or material feature of my design consists in the narrow case and strike provided with a flattened rim having bosses for the screw-holes and a marginal bead surrounding the rim.

Having thus described my invention, the following is what I claim as new therein and desire to secure by Letters Patent:

The design for a rim latch-case; substantially as herein shown and described.

HENRY R. TOWNE.
